UNITED STATES PATENT OFFICE.

STERLING W. WARNER, OF BOUND BROOK, NEW JERSEY, ASSIGNOR TO PATHÉ EX-
CHANGE, INC., OF NEW YORK, N. Y., A CORPORATION OF NEW YORK.

FILM REEL.

Application filed April 26, 1927. Serial No. 186,635.

This invention relates broadly to improvements in reels and more particularly to reels for use with motion picture apparatus and on which motion picture films are adapted to 5 be wound.

An object of the invention is to provide a reel adapted to be put on and taken off a spindle or shaft and having means for cooperating with the spindle whereby when put 10 on the spindle it is automatically locked in position and relative movement both longitudinal and rotative between the reel and the spindle is prevented.

Another object of the invention is to provide 15 a reel composed entirely of sheet metal elements which may be easily stamped or otherwise formed so that the cost of constructing the reel is low and a reel of light weight is obtained.

Another object of the invention is to provide 20 a reel in which the inner end of the film may be secured to the hub easily and readily and the reel loaded with facility.

With the above and other objects in view, 25 the invention further resides in the details and features of construction more particularly pointed out in the following description of the accompanying drawings forming a part of this specification.

30 In the drawings:

Figure 1 is a side elevational view of a reel constructed in accordance with the present invention;

Figure 2 is a transverse sectional elevational view through the reel illustrated in 35 Figure 1 showing a spindle for use in conjunction therewith;

Figure 3 is a perspective view illustrating certain features of the reel;

40 And Figure 4 is a perspective view of the spindle.

Referring now more particularly to the drawings, which show by way of illustration and example the preferred embodiment of 45 this invention and to the details of which I do not intend to be confined, the invention is disclosed as exemplified in a reel which comprises two side discs or flanges 11 and 12 spaced and supported by a hub 13 which 50 is provided with tongues 14 extending tightly into slots 15 in the discs or flanges. The discs or flanges are formed of sheet metal and preferably have a series of large apertures 16 extending in a general circular direction around their axis. The hub 13 is also

composed of sheet metal bent into cylindrical form and is preferably provided with a transverse slot 17. One of the apertures in the side of one of the discs is elongated in the direction of the axis or center of the disc 60 as indicated at 18 to expose the end of the slot 17 so that the inner end of the film may easily be slid into the slot and secured within the hub member in any suitable way. The provision of the aperture 18 facilitates the 65 loading of the reel and allows access to the interior of the hub and the film to be inserted in the slot from the side as well as in a tangential direction.

Means are provided for mounting the reel 70 on a driving shaft or spindle 19, which in the embodiment of the invention illustrated is preferably in the form of a rectangular core member comprising a channel element 20 and a plate element 21, the latter being adapted to form the upper side of the rectangular core member. It will be understood that the invention may be practiced with a core of any number of sides and is not limited to a four sided core. The ends 75 of the elements 20 and 21 are provided with lips or tongues 22 which are adapted to be bent over on the exterior of the side flanges or discs and serve the dual purpose of adding rigidity to the resulting reel and preventing movement of the elements 20 and 21 with respect to the side disc. As will be noted from Figure 3, the elements 20 and 21 also are each composed of sheet metal and the element 21 has a transverse ridge 23. 80 The upper edges of the two sides of the channel shaped element 20 are provided with slots 24, for the accommodation of the ridge 23, when the elements 20 and 21 are assembled in the reel.

In the form of the invention illustrated, the reel is adapted to fit on the rectangular end 25 of the spindle or shaft 19 and by reason of the multi-sided construction of the core of the reel and the end of the spindle 100 relative rotative movement between the spindle and the reel is prevented and the spindle and reel rotate as a unit. The spindle is also preferably provided with a collar 26 forming a shoulder against which the reel 105 abuts when slid upon the end of the spindle. One side of the rectangular end of the spindle has a transverse slot 27 into which the ridge 23 snaps when the reel is mounted in service on the spindle. The element 21 being 110

composed of sheet metal has sufficient resiliency and yields sufficiently to permit the reel to be slid on the end of the spindle without interference by the ridge 23.

- 6 When the reel is placed upon the spindle, the ridge 23 snaps into the slot 27 and provides a locking means for preventing longitudinal movement of the reel with respect to the spindle. The locking engagement of
10 the ridge and slot can however be broken by the application of sufficient force to overcome the resilient tendency of the element 21 to hold the ridge in the slot and the reel may be taken off the spindle without difficulty.

It will thus be seen that there is provided in this invention a construction which is simple in character, of low manufacturing cost, and of light weight and yet one which is efficient, rugged and adapted for severe conditions of service.

It will be understood that the invention is not limited to the specific construction described but that various alterations and modifications may be made in the embodiment illustrated without departing from the spirit and scope of the invention.

Having thus fully described my invention, what I claim as new and desire to secure by Letters Patent is:

1. A reel comprising two spaced side discs, 30 a core member between said discs, said core member being composed of a plurality of sides of sheet metal to adapt it for disposition on a multi-sided spindle, and a projection on the interior of the core member 35 adapted to snap into a depression on the spindle when the reel is placed on the spindle.

2. A reel comprising two spaced side discs, 40 a core member between said discs, said core member being composed of a sheet metal channel element and a plate element, a transverse ridge on the plate element adapted to fit in slots in the upper edges of the channel element and tongues on the ends of the 45 plate and channel elements bent over on the exterior sides of the discs.

In testimony whereof, I have signed my name to this specification this 20th day of April 1927.

STERLING W. WARNER.
